UNITED STATES PATENT OFFICE.

FRANCOIS JOSEPH DE SPOTURNO COTY, OF PARIS, FRANCE, ASSIGNOR TO COTY, INC., OF NEW YORK, N. Y., A CORPORATION OF DELAWARE.

DESIGN FOR A GLASS JAR.

Application filed November 30, 1926. Serial No. 19,887. Term of patent 14 years.

To all whom it may concern:

Be it known that I, FRANCOIS JOSEPH DE SPOTURNO COTY, a citizen of the Republic of France, residing at Paris, France, have invented a new, original, and ornamental Design for a Glass Jar, of which the following is a specification, reference being had to the accompanying drawing, forming a part thereof.

In the drawing,
Figure 1 is a perspective view of my design, and
Figure 2 is a top view thereof.

I claim:

The ornamental design for a glass jar substantially as shown.

FRANCOIS JOSEPH de SPOTURNO COTY.
